By Wm. Wm. Crampton,
His atty.

UNITED STATES PATENT OFFICE.

LEO A. KRUPP, OF FINDLAY, OHIO, ASSIGNOR TO THE BUCKEYE TRACTION DITCHER COMPANY, OF FINDLAY, OHIO, A CORPORATION OF OHIO.

EXTERNAL-WRENCH HEAD.

1,315,314.

Specification of Letters Patent.

Patented Sept. 9, 1919.

Application filed April 21, 1919. Serial No. 291,620.

To all whom it may concern:

Be it known that I, LEO A. KRUPP, a citizen of the United States, and a resident of Findlay, in the county of Hancock and 5 State of Ohio, have invented a certain new and useful External-Wrench Head; and I do hereby declare the following to be a full, clear, and exact description of the invention, such as will enable others skilled in 10 the art to which it appertains to make and use the same, reference being had to the accompanying drawings, and to the characters of reference marked thereon, which form a part of this specification.

15 This invention relates particularly to wrenches of the external type for use in turning coupling collars or the like into threaded engagement with pipe ends, or for use in gripping and imparting rotation to 20 any other cylindrical object.

The object of my invention is the provision of an apparatus of the class described which is simple, durable and efficient in its construction, easy to operate and adapted 25 to automatically grip an article to effect a turning thereof in either direction. Further objects and advantages of the invention will be apparent from the following detailed description.

30 While the invention, in its broader aspect, is capable of embodiment in numerous forms, a preferred embodiment thereof is illustrated in the accompanying drawings, in which,—

35 Figure 1 is a front elevation of a wrench head embodying the invention with parts broken away and removed; Fig. 2 is a central vertical section of the wrench head and driving connection, and Fig. 3 is a front elevation thereof with the front face plate removed.

Referring to the drawings, 1 designates the body ring of a wrench head embodying the invention, 2 and 3 the front and rear 45 face plates of annular form secured to the respective sides of said ring and co-operating with the outer peripheral side thereof to form an annular recess 4 in which a collar 5 is mounted for free turning movements. 50 This collar is provided at opposite sides thereof with handholds 6. The body ring 1 and face plates 2 and 3 are secured together in assembled relation by a plurality of screws or bolts 7 which, in the present instance, are 55 shown as being threaded into openings in

the face plate 2 and extending therefrom through registering openings in the body ring and face plate 3 which are held in position by a nut on the outer end of the bolt.

The body ring 1 is provided in its inner 60 peripheral edge or side with a plurality of recesses 8 which are elongated circumferentially of the ring and have their bottom walls disposed tangentially to a common circle described about the ring axis, the longitudinal center of each recess being approximately coincident with a radius of the ring disposed at right angles to the recess bottom.

The jaw shoe 9 is mounted in each recess 70 8 in position for its ends to extend in both directions beyond the longitudinal center of the recess and each end is provided with a jaw 10, the teeth of which are arranged in a plane which is inclined with respect to the 75 recess bottom and is tangent to a circle described about the ring axis. The toothed or gripping surfaces of the two jaws 10 of the shoe 9 are inclined in opposite directions and have their teeth directed in opposite directions so that one jaw is adapted to act to 80 drive an engaged member in one direction with the wrench head and the other jaw is adapted to drive an engaged member in the opposite direction upon a turning of the 85 head in such direction. Each shoe 9 is held within its recess for sliding movements longitudinally thereof by a screw 11, which passes through a longitudinal center slot in the shoe and threads into the bottom of the 90 recess. A spring-pressed detent 12 is carried by the body ring 1 for each shoe 9 and is adapted to engage a recess 13 in the shoe bottom and coat therewith to yieldingly 95 retain the shoe in neutral position.

When the shoe is in neutral position each jaw 10 thereof has a portion of its teeth projected to a slight extent into the ring opening in position to coat with a cylindrical article which is slightly smaller than the opening and inserted therein so that upon a turning of the head in one direction the jaw at the forward end of each shoe relative to the direction of turning of the head will engage the article and have its grip 100 tightened thereagainst by reason of the shoe carrying the jaw sliding from neutral position toward the opposite end of its recess so as to project a greater portion of the gripping jaw from the recess, as is apparent. 110

If the head is turned in the opposite direction when the jaw shoes are in neutral position, the same action will take place with respect to the other jaw of each shoe. By providing means for yieldingly holding the jaws in neutral position, the removal and insertion of an article from and into engagement with the wrench head is facilitated. The jaws 10 are preferably made separate from the shoes 9 and attached thereto by screws 14 or in any other suitable manner to facilitate a replacement of the jaws when worn or broken.

The head is attached at its rear side to a drive shaft 15 axially disposed with respect to the head through the medium of a suitable universal joint. This joint, in the present instance, comprises a cross-beam 16 on the end of the shaft 15 through which a pintle 17 axially extends and has its ends journaled in opposite sides of a circular yoke 18, which yoke has trunnions projecting from opposite sides thereof at right angles to the pintle 17 and journaled in bearing lugs 19 provided on the rear face plate 3. The shaft 5 may be connected to any suitable power means.

I wish it understood that my invention is not limited to any specific construction, arrangement or form of the parts as it is capable of numerous embodiments and changes without departing from the spirit of the claims.

Having thus described my invention, what I claim as new, and desire to secure by Letters Patent, is,—

1. An external wrench head having an article receiving opening therein and provided with an internal recess which is open to the head opening, a shoe mounted in the recess for sliding movements longitudinally thereof and in tangential relation to a cir-

cle concentric to the head axis, article gripping jaws carried at opposite ends of the shoe in exposed relation to the head opening and having their gripping faces oppositely inclined, one jaw of the shoe being adapted to grip an article on which the head is mounted when the head is turned in one direction and the other jaw being adapted to grip the article when the head is turned in the opposite direction, the shoe sliding to accommodate the gripping action, and means coacting with the shoe to yieldingly hold it in neutral position.

2. In an external wrench head, a body ring, front and rear face plates attached thereto and co-operating therewith to form an external peripheral recess, a collar loosely mounted to turn in said recess, said body ring having an internal recess elongated in a plane intersecting the head axis at right angles and the recess having its bottom disposed in tangential relation to a circle concentric to the head axis with its longitudinal center substantially coincident with a radius of the head at right angles to the recess bottom, a shoe mounted in the internal recess for longitudinal movements therein and having an article gripping jaw at each end, each of which jaws is movable into article gripping position by movements of the shoe toward the opposed end of the recess, one jaw of each shoe being adapted to grip an article on which the head is mounted when the head is turned in one direction and the other jaw of each shoe being adapted to grip the article when the head is turned in the opposite direction, and rotatable driving means connected to said head.

In testimony whereof, I have hereunto signed my name to this specification.

LEO A. KRUPP.
